UNITED STATES PATENT OFFICE

WILHELM KURZE, OF HANOVER, GERMANY, ASSIGNOR TO LANGE AND GEILEN, OF HALLE, SAALE, GERMANY, A GERMAN FIRM

CENTRIFUGAL MOLD FILLING APPARATUS

Application filed May 2, 1931, Serial No. 534,651, and in Germany May 26, 1928.

Applications have been filed in Germany, May 26, 1928, and Feb. 28, 1929.

This invention relates to apparatus for filling sand into molds, and particularly into mold boxes, which are used in foundries. It has already been recognized that it is important, when the foundry sand is introduced into the mold box, to prevent, as far as possible, the simultaneous introduction of air. 10 Hitherto, however, experiments in this respect have not led to any useful results.

In accordance with the invention, apparatus is provided, by means of which a shower of foundry sand, substantially free from air, is arranged to be thrown with great force into the mold boxes, so that the finished molds are very firm and homogeneous. Such apparatus may comprise rapidly-revolving, convex (rearwardly curved) projection blades 15 arranged in a casing, which propel the air before them outwards through apertures in the casing, the foundry sand being introduced immediately above the projection opening of the casing by means of a worm conveyer. In 20 this way, at the moment when the blades strike the sand, the air in front of the plates has already been almost completely removed. Insofar as there is still some air remaining in front of the blades after the latter have encountered the stream of sand supplied, this air is arranged to be conveyed inwardly and be removed therefrom, the blades engaging the sand only at their outer ends. By arranging the sand supply just 25 above the projection opening, a very even shower of sand is thrown forcibly out of the apparatus.

The air which is still in front of the blades when the projection of sand takes place may 40 be removed through an air aperture and damper, which are provided adjacent to the projection opening of the casing.

The constant supply of sand under pressure to the projection blades is essential for 45 the removal of air, which would be detrimental to the manufacture of the molds, and for regular operation of the apparatus. This is effected, in accordance with one constructional embodiment of the invention, by means 50 of a worm conveyer located in a conduit se-

cured to the casing just above the projection opening. The foundry sand is supplied to the conduit from above from a vertical hopper, in which a distributor may be provided.

In the accompanying drawing a constructional embodiment of the invention is illustrated, Figure 1 being a front elevation, Figure 2 a partial section on line II-II of Fig. 1, and Figure 3 a plan view of Fig. 1.

The box-shaped frame 1 of the machine 60 comprises a table 2, on to which the foundry sand is cast, a projection casing 3, in which is located a projection opening 4, sand-supply members, which are described herein-after, and the driving mechanism. In the 65 floor of the table 2, over which scrapers 17 are adapted to rotate, an opening 6 covered by a sieve 5 is located, this opening leading to a vertical hopper 7. In the hopper 7 is provided a distributor 8, which consists of a shaft 70 45, provided with one or more raking arms 46 thereon, one only being shown. Shaft 45 is driven through a belt or chain 49 from shaft 21, hereinafter referred to. The hopper 7 leads into a conduit 9, in which is located a 75 worm 10. The conduit 9 is secured to the casing 3 just above the projection opening 4.

In the casing 3 is located a rotatable disc 11, to which are secured two or more projection blades 12, formed convex in the direction of rotation. On the circumference of the casing apertures 13 are provided, and just above the sand supply conduit 9 is an air vent 14. Adjacent to the projection opening 4, the casing contains an air aperture 15 and a 80 damper plate 16, which is U-shaped in cross-section, see Fig. 2.

The apparatus, as illustrated by way of example, is driven by an electric motor 18, the speed of which may be regulated between wide 90 limits. On shaft 28 of the motor is a pulley 29, which drives pulley 30, mounted on shaft 20, carrying the disc 11, through belt 19. A second shaft 21 is driven from shaft 20 by belt 22 and pulleys 31 and 32. A bevel gear 33 95 is keyed on shaft 21 and drives bevel gear 34 on vertical shaft 39, which drives the scrapers 17 through bevel gears 40 and 41, shaft 42 and bevel gears 43 and 44. Bevel gear 34 meshes with bevel gear 35, the hub of which 100

carries spur teeth 36, in mesh with spur gear 37 on shaft 38, which carries the worm 10. In order that the entire apparatus may be readily transported and oscillated, trunnions 5 23 are provided on the frame 1 of the apparatus.

When the apparatus is operated without sand being supplied, the rotatable disc 11 acts with its blades 12 as an air propeller. The air 10 propelled by the blades passes outwards through the apertures 13 and the vent 14. When foundry sand is conveyed to the conduit 9 by the worm 10, the blades 12 strike the sand with their outer ends, after the greater part of 15 the air propelled by the blades has been removed. When the blades strike the sand the latter is projected through the projection opening 4 and air thrown out by the blades near the projection opening after the sand 20 has left the blades will strike the damper plate 16 and be deflected laterally through the latter which is hollow to the extreme left side (Figure 1) of the apparatus, or be deflected by the damper plate 16 through aperture 15, 25 a suction being exerted at the aperture 15 in view of the passage of air from the interior of the casing 3 through the aperture 25 in the lower part of the casing and apertures 26 and 27. The projection opening 4 in the casing 30 is substantially tangential to the circular path of the outer ends of the blades. As the sand supply conduit 9 is located immediately above the projection opening 4 and extends substantially radially to the casing, a 35 shower of sand is forcibly thrown out, which is substantially free from air.

The apparatus illustrated in the drawing is to be considered only as a constructional example. For instance, the number of projection blades 12 may evidently be altered. 40 The sand may also be cast initially into the hopper 7 by means of a chain conveyer or a screw conveyer instead of from the table 2 provided with scrapers 17. The projection 45 blades 12 may be integral with the disc 11 or alternatively connected to it. An interchangeable armour-plate 24 may be provided adjacent the projection opening 4 of the casing.

50 These and other modifications, which will be evident to those skilled in the art, may be made without exceeding the scope of the invention.

Having now described my invention, what 55 I claim as new and desire to secure by Letters Patent is:

In centrifugal mold-filling apparatus, the combination of a casing having a tangential sand outlet, a radial sand inlet, air outlets 60 above said inlet and an air outlet at the side of said tangential outlet; rotary means in said casing to drive air out of the same and to project the sand from said tangential outlet, and a damper plate projecting into said 65 tangential outlet to deflect air, carried along

with the sand, through said adjacent air outlet.

In testimony whereof I have signed my name to this specification.

WILHELM KURZE.
